INDUCTION HEATING APPARATUS

William F. Wells, Baltimore, Md., assignor to
Westinghouse Electric Corporation, East Pitts-
burgh, Pa., a corporation of Pennsylvania

Application June 15, 1946, Serial No. 676,912

3 Claims. (Cl. 219—13)

1

While my invention has broader aspects, it is described herein with special emphasis on an induction heating apparatus for heat-treating helical or coil springs having one or both end turns contacting the next adjacent turn so that the spring has, in effect, an electrically short-circuited turn.

When it is attempted to inductively heat such coil springs in the customary manner, that is, with magnetic field lines parallel to the axis of the spring, overheating is encountered in the turn which is shorted on itself or contacts an inner turn. By heating such a spring inductively with magnetic field lines passing through the spring substantially perpendicularly to its axis, in accordance with my invention, there is no electric current flow around the short-circuited turn. The spring is uniformly heated without localized overheating, especially when the spring is also rotated about its axis so that all of its sections are subjected to the different parts of the heat-producing alternating magnetic field.

My invention has for another objective the heat-treatment of round metal objects or work-pieces within an induction-heating coil shaped to a contour of the work-pieces. Thus, for example, for an elongated helical spring having turns of substantially the same diameter, I provide an induction-heating coil of rectangular shape which is elongated in the length-direction of the spring.

Other objects, features and innovations of my invention will be apparent or discernible from the following description of the preferred embodiment, which description is to be taken in conjunction with the accompanying drawing, in which:

Figure 1 is a schematic perspective view of an application of my invention for heating helical springs, with a quenching means omitted for clarity;

Fig. 2 is a sectional view substantially on the line II—II of Fig. 1 with a quenching means added; and

Fig. 3 is a schematic wiring diagram showing the principal parts of a second system utilizable with the apparatus of Figs. 1 and 2.

A specific work-piece that can be heated in the apparatus shown in Figs 1 and 2 constitutes a helical spring 2 of a steel that can be hardened. The spring 2 has end turns 4 terminating in tip-ends 6 which press against, or otherwise contact, the adjacent metal of the next turn of the spring so that, electrically speaking, a complete path is provided for current-flow around each end-turn of the spring.

The spring 2 is heated when an induction-heating coil, indicated in its entirety by the reference numeral 8, is energized by an alternating-current source of suitable frequency. The coil

2

8 comprises a number of rectangular turns of hollow copper tubing that can be water cooled.

The spring 2 is supported on a pair of horizontally-directed rotatable rods or rollers 9 and 10 of a suitable heat-resistant material. A non-metallic refractory, such as silicon carbide, is satisfactory. The rollers 9 and 10 are rotatably supported in a frame which is indicated in its entirety by the reference numeral 12; the frame comprising a stationary member 14 in which the roller 9 is rotatably supported, and a second member 16 in which the roller 10 is rotatably supported. The frame-member 16 is slidable for purposes to be later described. Ends of the rollers 9 and 10 extend beyond the frame-members 14 and 16, and have sheaves 18 adapted to be rotated by a driving wheel 20 with which they mesh when in normal work-receiving position. The driving wheel 20 is driven, through gearing 22, by a motor driven shaft 24 which also drives, through the gearing, a timer shaft 26 having a cam 28 bearing against a roller 30 rotatably secured to the slidable frame-member 16.

The frame-member 16 is provided with rods 32 which are slidably received in holes or journals in the stationary member 14, and with a rod 34 slidably received in a hole in a stationary post 36 which may be part of the stationary frame-member 14, if desired. Anchored to spaced stationary lugs 38, on opposite lateral sides of the post 36, are a pair of tension springs 40 which tends to pull the slidable frame-member 16 away from the stationary frame-member 14 and toward the post 36 which therefore also serves as a stop.

During rotation of the time shaft 26, a circular cam-surface 42, on the cam 28, engages the roller 30 and keeps the frame-member 16 in the position shown while the driving wheel 20 rotates the rollers 9 and 10. The rollers cause the spring 2 to rotate about its own axis which is parallel to a long side of the rectangular induction-heating coil 8. If the coil 8 is energized, the spring will be heated while it is being rotated. When the cam has been rotated to a point where its indent surface 44 reaches the roller 30, the tension springs 40 yank the frame-member 16 toward the post 36, pulling the roller 10 along with it, so that the heated spring 2 drops between the rollers 9 and 10 into a quench tank 45 immediately below the rollers.

A control may be provided for timing the heating of the spring or work-piece 2. To this end a switch 46 is provided which is normally biased to open position but forced into closed position by the slidable frame-member 16 in its work-receiving position shown in Fig. 1. When the springs 40 move the slidable frame-member 16, the switch 46 opens automatically.

Referring to Fig. 3, the switch 46 controls a relay 48 in a circuit 50; the relay being of a type having an armature or core 52 which it cannot, upon energization, raise from a back or released position, but which it can maintain in front or holding position if the core 52 is otherwise moved to this front position. A handle 54 is shown attached to the bottom of the core 52, by which the core can be manually raised into the front position where it will be held if the relay 48 is energized.

The core 52 operates a plurality of movable contacts 56 and 58. The movable contact 56, in front position, is instrumental in completing a circuit 60 to a motor 62 which drives the shaft 24. The movable contact 58, in front position, is instrumental in completing a circuit 64 to a relay 66 which, in energized condition, completes a circuit 68 for energizing the induction-heating coil 8.

In operation, while the core 52 of the relay 48 is in its back position and the frame-member 16 is in its work-receiving position, so that the switch 46 is closed, a spring 2 may be placed upon the rollers 9 and 10. The core 52 may then be pushed into its front position where it will be automatically held because the circuit 50 is complete. In front position of the core, the contact 56 energizes the motor 62 which rotates its shaft 24 and hence the drive wheel 28 and the spring 2. At the same time, the contact 58 causes application of heating power to the induction-heating coil 8 so that the spring 2 is heated by magnetic flux passing axially through the coil 8, that is, perpendicularly to the axis of the spring 2. At the same time, the shaft 24 of the motor 62 drives the cam 28 so that its surface 42 moves past the roller 30 until the indent surface 44 of the cam reaches the roller 30. The springs 49 can then pull the slideable frame-member 16 toward the post 36, separating the rollers 9 and 10. The heated spring 2 is consequently released and drops into the liquid in the quench tank 45. As the frame-member 16 is withdrawn, the switch 46 opens and deenergizes the relay 48 which drops its core 52, moving the contacts 56 and 58 to open or back position. Opening of the circuits 62 and 64 by these contacts deenergizes the motor 62 and disconnects the power supply from the coil 8.

For restoring the apparatus to heat-treating condition, a separate manually-operable switch 70 can be temporarily operated to energize the motor 62 and restore the cam 28 to a position where it forces the frame-member 16 into work-receiving position; or the cam driving means may be manually turned.

Obviously the speed of rotation of the rollers 9 and 10, and hence the spring 2, will be determined by the diameter of the driving wheel 28 and by the gearing reduction in the gear box 22; and similarly the timing of the heating of the spring 2 will be controlled by the gearing in the box 22 between the driving shaft 24 and the cam shaft 28, and by the peripheral length of the outer surface 42 of the cam 28.

It is to be observed from Figs. 1 and 2 that the inside of the rectangular multi-turn induction-heating coil 8 provides a work-receiving space of sufficient size and depth to encompass substantially the entire spring 2. The rollers 9 and 10 lie under this work-receiving space of the coil 8

and support the spring 2 so that the short-circuited end turns 4 of the spring face the shorter opposed turn-sides of the coil 8 and the axis of the spring is parallel to the longer opposed turn-sides of the coil 8. The rollers 9 and 10 must provide a cylindrical spring-supporting surface which is axially sufficiently elongated to let the spring 2 roll on the surface without a turn of the spring catching on an end of the rollers.

While I have described my invention in its preferred form, it is evident that its teachings are generally applicable to any suitable elongated round work-piece capable of being rotated about a central axis extending in the direction of its length. It is also evident that equivalent parts may be substituted and modifications can be made in the apparatus herein disclosed to accommodate such and other work-pieces for heat-treatment in accordance with the general teachings of my invention.

I claim as my invention:

1. Induction heating apparatus suitable for heating a helical spring having shorted end-turns, comprising a helical induction heating coil generally rectangular in a substantially horizontal cross-sectional plane, said coil having an upstanding axis and comprising substantially straight opposite turn-sides, a pair of elongated substantially straight horizontal rollers under said coil substantially parallel to a pair of said opposite turn-sides, said rollers being continuous in length for a major part of the length of each of the last said turn-sides and adapted to support a helical spring with its axis parallel to said turn-sides.

2. A helical induction heating coil generally rectangular in a substantially horizontal cross-sectional plane, said coil having an upstanding axis and comprising a plurality of turns, the coil turns having substantially straight opposite turn-sides, means to rotatably support a workpiece entirely within said coil for rotation inside of said coil about a horizontal axis, said means comprising a pair of adjacent work-supporting and rotating substantially horizontal rollers under said coil, parallel to a pair of said turn-sides.

3. An invention including that of claim 2 but further characterized by timer means for periodically spreading said rollers, whereby to allow work on said rollers to drop.

WILLIAM F. WELLS.
